MAGNET CASTING

Mitchell P. Christensen, Chicago, Ill., assignor to
Belden Manufacturing Company, a corporation
of Illinois

Application May 26, 1941, Serial No. 395,243

12 Claims. (Cl. 29—155.5)

My invention relates generally to the provision of inexpensive, small, permanent magnets for use in connection with dynamic sound producing mechanisms, such as radio loud speakers and the like.

In recent years magnetic metals of improved alloy compositions have been developed out of which permanent magnets having much greater magnetic strength than previously obtainable may be formed. These improved magnetic metals generally comprise various nickel-aluminum alloys of iron. A very important application of these improved permanent magnets of greater magnetic strength has been in connection with loud speakers for radios, record players, and the like. Because of the requirements in respect to minimum space and weight, ordinary iron or steel permanent magnets do not have sufficient magnetic strength per unit density to permit them to be used to provide the magnetic field in these loud speaker devices, and it was the practice prior to the development of the improved magnetic alloys to use electromagnets for providing the magnetic field in connection with these loud speakers. However, these improved magnetic alloys provide permanent magnets having sufficient magnetic strength per unit density to permit them to replace the electromagnets, especially in connection with the smaller size of loud speakers where low cost and low electrical power demand are very important factors.

The mounting of the small permanent magnets in the loud speakers has presented somewhat of a problem to the manufacturers of these devices. In order to provide the greatest magnetic field strength with minimum flux leakage, it is desirable to make the magnets in the form of small tapered blocks whereby one pole is narrower than the other. In one of the best known arrangements a small cylindrical pole piece of high permeability is mounted on the narrow pole face of the tapered magnet and the magnet is mounted in a stirrup or similarly shaped pole piece member which extends from the base or large pole face of the permanent magnet around the sides thereof and into close proximity with the small pole piece so as to provide a magnetic field therebetween.

It has been found that the most practical way, or at least the most convenient way, of mounting the tapered magnets in permanent magnet structures of this type, is to bolt the magnet in place by the use of a bolt or screw which passes through a central hole or passageway extending from pole to pole through each magnet. One

end of the bolt or screw engages the small cylindrical pole piece on the narrow pole face of the magnet and the opposite end engages the stirrup or like-shaped pole piece or member. By tightening the bolt or screw, the small pole piece is drawn into contact with the narrow pole face of the permanent magnet while the permanent magnet is held in place in the stirrup.

Because of the brittleness and difficultly machineable character of the permanent magnet alloys, the provision of these central holes in an economical manner has given considerable trouble. In fact, it has been found that the metal is so hard and brittle that it is impractical to drill the holes by ordinary manufacturing methods. Accordingly, it has been necessary in casting these small tapered magnets to use small cores to provide the central holes therethrough. This practice has materially increased the cost of producing these small magnets and various attempts have been made to eliminate this expensive item of manufacture. In one case attempts were made to cement the small pole pieces onto the narrow poles of the tapered magnets and to cement the magnets to the stirrups or like members; this was not a satisfactory arrangement. As another alternative, small specially shaped individual castings of magnetic metal were made in such shapes that cores were not necessary. However, the cost of making such individual castings was high and the castings did not have the optimum shape for maximum efficiency in respect to greatest magnetic field strength with minimum flux leakage. Other procedures have likewise proven unsatisfactory, and as a result there has been a substantial need and demand for providing small magnets in the form of tapered blocks having holes formed therethrough in a less costly manner than known heretofore.

The object of my invention, generally stated, is to provide small magnets of the type described above having central holes passing therethrough by a method involving certain novel-shaped bar castings, whereby the central holes are formed without the necessity of drilling or of using small cores in casting. The invention makes possible the manufacture of these small magnets on a quantity production scale at a very low cost. The magnets may be conveniently provided in the desired shape giving maximum field strength with minimum flux leakage without sacrifice or compromise in respect to magnetic field efficiency, size, mounting arrangement or any other factor.

Other objects of the invention will in part be obvious, and in part stated hereinafter.

For a more complete understanding of the nature and scope of my invention, reference may be had to the following detailed description thereof taken in conjunction with the accompanying drawings, in which:

Fig. 1 is a perspective view of a bar-shaped casting of magnetic metal adapted to be broken up into uniformly shaped pieces combinable to form small magnets having central holes passing therethrough, the shape of the casting constituting an important feature of this invention;

Fig. 2 is a vertical sectional view taken on line 2—2 of Fig. 1;

Fig. 3 is a fragmentary side elevational view of a machine by which the bar-shaped casting of Fig. 1 may be conveniently chopped or broken into short lengths;

Fig. 4 is a perspective view of one of the short lengths of the bar of Fig. 1 as chopped off in the machine of Fig. 3;

Fig. 5 is a diagrammatic view illustrating the manner in which the short length of Fig. 4 may be broken in two by a hammer at the thin section thereof;

Fig. 6 is a perspective view of one of the uniformly shaped pieces obtained by breaking short bar lengths as shown in Fig. 4 in the manner shown in Fig. 5;

Fig. 7 is a perspective view showing two complementary pieces of the type shown in Fig. 6 combined together to form a small tapered magnet having a central hole formed therethrough;

Fig. 8 is a side elevational view, partly broken away showing the manner in which the two-piece magnet of Fig. 7 may be assembled as part of the permanent magnet structure of a loud speaker;

Fig. 9 is a sectional view taken on line 9—9 of Fig. 8;

Fig. 10 is a perspective view of an alternative form of bar-shaped casting of magnetic metal;

Fig. 11 is a vertical sectional view taken on line 11—11 of Fig. 10;

Fig. 12 is a perspective view of a short length into which the bar-shaped casting of Fig. 10 is adapted to be broken;

Figs. 13 and 14 are perspective views of the complementary pieces into which the short length of Fig. 12 may be broken at the thin section thereof; and

Fig. 15 is a perspective view showing the manner in which the pieces of Figs 13 and 14 may be combined to form a two-piece magnet having a hole passing therethrough.

In Fig. 1 of the drawings, a rectangular bar casting 10 is shown which may be readily cast in an easy manner without the use of cores. The bar 10 has a deep longitudinal channel 11 formed in the top face 12 thereof of such depth as to leave only a relatively thin section 13 interconnecting the portions of the bar on opposite sides of the channel. It will be noted that the sides of the channel 11 slope or taper inwardly at a substantial angle. A number of regularly spaced vertical grooves 14 are formed in the opposite sides of the bar 10, as shown. The grooves 14 are semi-cylindrical in shape, but it will be understood that they may take other forms if desired. After the bar 10 has been cast, the top and bottom faces 12 and 15 are smoothed and planed by grinding so that the thickness of the bar 10 between the faces will be uniform throughout. The bar 10 may be cast in any practical length.

When the bar 10 is cast or formed of a permanent magnetic metal, such as the nickel-aluminum alloys of iron, it will be of such hard-

ness and brittleness that it can be machined only with great difficulty, although it may be ground fairly readily. However, this brittleness or hardness permits the bar 10 to be readily chopped or broken into short lengths of predetermined size. Such a short length is shown at 16 in Fig. 4, and in Fig. 3 of the drawings a machine for forming these short lengths is shown.

The machine is indicated generally at 17 in Fig. 3, and comprises a bed member 20 which serves as a supporting base for the elements thereof. A block 21 is mounted on the base 20 and four upright posts 22 are supported thereon, as shown. A guide block 23 is supported by the four posts 22 adjacent to the upper ends thereof, and serves to guide the vertical up and down reciprocating movement of a post 24 carrying a block 25 on the lower end thereof.

The bars 10 are chopped into short lengths 16 by a pair of oppositely disposed knife-edged members or blocks 26 and 27. The lower knife-edge member 26 is securely mounted on the block 21, while the upper knife-edge member 27 is securely held on the lower face of the head 24. The lower knife-edge member 26 is stationary while the upper member 27 is moved up and down when the machine 17 is in operation by suitable power and control means connected with the post 24.

The bars 10 are adapted to be fed into the machine 17 on a narrow guide table 30 having a channel formed in the top thereof equal in width to the width of the bars 10. The floor of the channel in the table 30 is level with the height of the knife-edge 31 of the lower block 26 so that the bottom face of the bar 10 will rest on this cutting edge.

Ordinarily, the bar 10 will be chopped into short lengths 16 at points midway between the side grooves 14 as indicated in Fig. 3 by the broken line 32. In order that the bar 10 may be fed through the machine 17 in a convenient manner so that it will be broken midway between the vertical side grooves 14, a pair of spring mounted stops 33 may be provided on the opposite sides of the table 30 having small protuberances 34 which project into the side grooves 14. The stops 33 are carried on the loose ends of flexible spring members 35 which are riveted at their back ends 36 to the feeding table 30, as shown. A slight force or push is sufficient to advance the bar casting 10 from one set of opposite vertical grooves 14 to the other. Each time the bar 10 is stopped over the lower cutting block 26, the upper cutting block 27 will come down with a sharp blow across the top of the bar 10 and chop or break off a short length 16 thereof. The short broken lengths 16 may drop through the machine 17 through a notch 36 provided in the block 21 and a registering hole 37 provided in the base 20, as shown. It will be understood that certain other forms and designs of machines may be provided to chop up the bar-shaped castings 10 into the short lengths 16.

Since the short lengths 16 have only a thin section 13 connecting the two halves thereof, they may be readily broken in two as indicated in Fig. 5. As there shown, one of the short lengths 16 is inserted between the jaws of a vice 40 so as to be securely held. The jaws of the vice are so designed that the upper jaw 40 is shorter than the lower jaw 41. Each piece 16 is placed in the vice so that the lower jaw 41 projects midway underneath the thin connecting section 13 and a sharp blow from a hammer, the head of

which is indicated at 42, will easily break the piece 16 in two. The broken pieces are indicated at 43 in Fig. 6.

It will be seen that the fragment or piece 43, Fig. 6, has a top face 44 which originally constituted part of the top face 12 of the bar 10, Fig. 1, and an opposite wider bottom face 45 which originally constituted a portion of the bottom face 15 of the bar 10. One of the side faces 46 of the piece 43 includes one of the vertical side grooves 14 and originally constituted a portion of one of the opposite vertical sides of the bar 10. The face 46 and the groove 14 are perpendicular to the parallel faces 44 and 45. The face 47 opposite to the vertical face 46 is sloping and originally was part of one of the sloping sides of the channel 11 of the bar 10.

Each pair of the pieces 43 may be combined together so as to form a two-piece tapered magnet 50 having a central hole 51 passing therethrough as shown in Fig. 7. The narrow pole faces 44 of the pieces 43 are placed together side by side in plane alignment so that the two-piece magnet 50 is tapered from its base to the top. Each of the pieces 43 is magnetized so that the narrow faces 44 form pole faces of like polarity while the opposite faces 45 form the opposite pole faces of opposite polarity. Since the pieces 43 are placed together with like poles adjacent to each other, it will be seen that the pieces tend to repel each other and to separate and spread apart. However, when assembled in the magnet structure of a loud speaker, the pieces 43 are held together as will appear herein-after.

In Figs. 8 and 9 a permanent magnet structure for a radio loud speaker is indicated generally at 55 which has for the energizing element there-of a two-piece permanent magnet 56 which corresponds to the two piece magnet 50 of Fig. 7. A cylindrical pole piece 57 of high permeability is supported on the narrow pole face of the magnet 56 by a supporting flange 58, as shown. The opposite wide pole face of the magnet 56 fits against one side 60 of a stirrup-shaped pole piece 61. The cylindrical pole piece 57 and the permanent magnet 56 are held in assembled relationship in the stirrup-shaped pole piece 61 by a bolt 62 which passes through the central hole in the two piece magnet 56. The head 63 of the bolt 62 engages the back of the side 60 of the stirrup 61 while the inner threaded end thereof is screwed into the cylindrical pole piece 57 which is tapped to receive the same. It will be seen that by drawing down or tightening the bolt 62, the pole piece 57 is drawn down against the two-part narrow pole face of the magnet 56 and the magnet 56 is in turn held firmly against the inside of the stirrup 61. The bolt 62 draws the pole piece 57 in sufficiently tightly so as to hold the two pieces of the magnet 56 together and overcome the repulsion therebetween.

The stirrup 61 extends around the sides of the magnet 56 and has a hole formed in the side 64, opposite the side 60, which fits around the pole piece 57 so as to form an annular air gap 65 therebetween. The voice coil (not shown) of the speaker will fit in this air gap 65. A metal basket or spider 66 of the usual construction is provided on the left hand side of the stirrup 61 as shown in Fig. 8 and is adapted to support the usual vibrating or sound producing cone of the speaker. The metal basket 66 may be conveniently spot welded to the stirrup 61, or otherwise suitably secured thereto.

The two-piece magnet 56 is functionally equivalent to a similarly shaped magnet which is completely integral throughout. As far as the operation, assembly and ruggedness of the speaker is concerned, the two-piece magnet 56 is equally as satisfactory as an integral one. However, as pointed out above, the hole therethrough for accommodating the assembly retaining screw 62 is formed without difficulty and without the necessity of drilling or using cores in casting. Thus, the cost of the magnets 56 is materially reduced.

It was indicated above in connection with the description of the bar-shaped casting 10 of Figs. 1 and 2, that there was an advantage in having the long, longitudinal channel therethrough formed with tapering or inwardly sloping sides. In the first place, this taper permits the mold pattern of the casting to be easily removed from the mold, and in the second place, it provides the two-piece magnet with a taper which is very desirable. This taper allows the flux of the magnet 56 to be concentrated at a narrow pole space whereby a maximum of the magnetic flux will link across the annular air gap 65. In this manner the maximum strength of field flux is obtained with a minimum-sized magnet and with a minimum of flux leakage.

My invention may be practiced and embodied in several different modifications. Referring to Figs. 10 and 11 of the drawings, an alternative form of bar-shaped casting 70 of magnetic metal is shown which is adapted to be broken up to form into pieces which may be combined in pairs to form permanent magnets each having a hole passing therethrough. The bar casting 70 has two longitudinal channels 71 and 72 formed in the top and bottom surfaces thereof and placed off center toward one side. The channels 71 and 72 are vertically opposite so as to leave only a small narrow section 73 connecting the two parts of the bar 70. Regularly spaced, vertical side grooves 74 are formed in one of the sides of the bar 70, as shown. The grooves 74 are of substantial size so as to adequately accommodate a bolt or screw, such as the bolt 62 of Fig. 8.

The bar 70 may be chopped into short lengths 75 as shown in Fig. 12 according to the manner described in connection with the breaking of the bars 10 in the machine 17, Fig. 3 of the drawings. Each of the short lengths 75 contains one of the deep side grooves 74. In turn, each of the short lengths 75 may be broken in two 55 at the thin section 73 thereof so as to form the complementary pieces 76 and 77 shown in Figs. 13 and 14 respectively. Each complementary set or pair of pieces 76 and 77 may be combined together as shown in Fig. 15 so as to form 60 a magnet 78, having a central hole 79 passing therethrough. The hole 79 is formed by one of the vertical side grooves 74 and closed by the abutting side of the piece 76. The magnet 78 may be assembled in a permanent magnet 65 structure in the manner in which the magnet 56 is assembled in the permanent magnet structure 55, Fig. 8.

In the foregoing description of certain embodiments of my invention and in the appended claims 70 various pieces and elements have been shown or described by reference to certain positions. That is, the top and bottom faces, vertical sides, and other portions of the pieces have been referred to. It will be understood that such positions 75 may be changed, reversed, and altered and that

reference to certain positions has been for purposes of description only. Since certain further modifications and embodiments of the invention may be made without departing from the scope thereof, it is intended that all matter described hereinbefore or shown in the accompanying drawings, shall be interpreted as illustrative and not in a limiting sense.

I claim:

1. A casting of difficultly machinable permanent magnet metal shaped in the form of a bar having at least one longitudinal channel in either the top or bottom face thereof of such depth as to leave only a relatively thin section lengthwise connecting the portions of the bar-shaped casting on opposite sides of said channel, and having a plurality of grooves extending between the top and bottom faces in at least one side of the casting.
2. A casting of difficultly machinable permanent magnet metal shaped in the form of a rectangular bar having a deep longitudinal channel in either the top or bottom face thereof of such depth as to leave only a relatively thin section connecting the portions of the bar-shaped casting on opposite sides of said channel, and having a plurality of regularly spaced vertical grooves in the opposite sides thereof.
3. A casting of difficultly machinable permanent magnet metal shaped in the form of a rectangular bar having a deep longitudinal channel in the center of either the top or bottom face thereof of such depth as to leave only a relatively thin section connecting the two halves of the bar-shaped casting on opposite sides of said channel, and having a plurality of regularly spaced vertical grooves in the opposite sides thereof with the grooves on one side being directly opposite to those on the other side.
4. A casting of difficultly machinable permanent magnet metal shaped in the form of a rectangular bar having a deep longitudinal channel in the top face thereof with inwardly sloping sides and of such depth as to leave only a relatively thin section lengthwise of the bar connecting the portions of the bar on opposite sides of said channel, and having a plurality of regularly spaced vertical grooves extending between the top and bottom faces in at least one side of the casting.
5. A casting of difficultly machinable permanent magnet metal shaped in the form of a rectangular bar having a deep longitudinal channel in the top face thereof with inwardly sloping sides and of such depth as to leave only a relatively thin section lengthwise of the bar connecting the portions of the bar on opposite sides of said channel, and having a plurality of regularly spaced vertical grooves in the opposite sides thereof with the grooves on one side being directly opposite to those on the other side.
6. A casting of brittle permanent magnet metal shaped in the form of a rectangular bar having a pair of vertically opposite deep channels extending longitudinally in the top and bottom faces thereof of such depth as to leave only a relatively thin section therebetween, and having a plurality of regularly spaced vertical grooves in one side thereof.
7. The method of making magnets each having a hole therethrough which comprises, casting difficultly machinable permanent magnet metal in the form of a bar having at least one longitudinal channel in either the top or bottom
- 5 face thereof of such depth as to leave only a relatively thin section lengthwise connecting the portions of the bar on opposite sides of said channel, and having a plurality of grooves extending between the top and bottom faces in at least one side of the bar, chopping said bar into relatively short lengths, breaking each of said short lengths in two at the thin section thereof so as to form a plurality of complementary pieces, and combining the pieces together to form multi-piece magnets each of which has one of said side grooves forming a hole therethrough.
8. The method of making magnets each having a hole therethrough which comprises, casting difficultly machinable permanent magnet metal in the form of a bar having a deep longitudinal channel in either the top or bottom face thereof of such depth as to leave only a relatively thin section connecting the portions of the bar on opposite sides of said channel, and having a plurality of regularly spaced vertical grooves in the opposite sides thereof, chopping said bar into a number of relatively short lengths each of which includes a pair of opposite vertical grooves, breaking each of said short lengths in two at the thin section thereof so as to form a plurality of complementary pieces each of which has one of said vertical grooves in one face thereof, and combining the complementary pieces in pairs to form two-piece magnets with the vertical grooves of each pair of pieces combined to form a hole through each of the two-piece magnets.
9. The method of making magnets each having a central hole therethrough which comprises, casting difficultly machinable permanent magnet metal into the form of a bar having a deep longitudinal channel in the center of either the top or bottom face thereof of such depth as to leave only a relatively thin section connecting the two halves of the bar on opposite sides of said channel, and having a plurality of regularly spaced vertical grooves in the opposite sides thereof with the grooves on one side being directly opposite to those on the other side, chopping said bar at right angles to its length into relatively short lengths each of which includes one set of said opposite vertical side grooves, breaking each of said short lengths in two at the thin section thereof so as to form a plurality of uniformly shaped complementary pieces each of which has one of the vertical grooves in one face thereof, and combining the complementary pieces in pairs so as to form two-piece magnets with the vertical grooves of each pair of pieces placed together so as to form a central hole through each of the two-piece magnets.
10. The method of making tapered magnets each having a hole therethrough which comprises, casting difficultly machinable permanent magnet metal in the form of a rectangular bar having a deep longitudinal channel in the top face thereof with inwardly sloping sides and of such depth as to leave only a relatively thin section lengthwise of the bar connecting the portions of the bar on opposite sides of said channel, and having a plurality of regularly spaced vertical grooves in the opposite sides thereof, chopping said bar at right angles to its length into relatively short lengths, breaking each of said short lengths in two at the thin section thereof so as to form a plurality of uniformly shaped complementary pieces each of which has one face which constituted a portion of said top face of the bar and an opposite parallel wider face

which constituted a portion of the bottom face of said bar, each of said pieces having another face which is perpendicular to said opposite parallel faces thereof and which constituted a portion of one of the vertical sides of said bar and includes one of said vertical side grooves therein, and another face of each piece being opposite to said perpendicular face thereof and which constituted a portion of one of said sloping channel sides; and combining the complementary pieces in pairs so as to form tapered two-piece magnets with the vertical grooves of each pair of pieces placed together so as to form a hole through each of the tapered two-piece magnets.

11. The method of making tapered magnets each having a central hole therethrough which comprises; casting difficultly machinable permanent magnet metal in the form of a rectangular bar having a deep longitudinal channel with inwardly sloping sides in the top face thereof of such depth as to leave only a relatively thin section lengthwise of the bar connecting the portions of the bar on opposite sides of said channel, and having a plurality of regularly spaced vertical grooves in the opposite sides thereof with the grooves on one side being directly opposite to those on the other side; chopping said bar at right angles to its length midway between each set of opposite vertical grooves into a number of relatively short lengths; breaking each of said short lengths in two at the thin section thereof so as to form a plurality of uniformly shaped complementary pieces each of which has one face which constituted a portion of said top face of the bar and an opposite parallel wider face which constituted a portion of the bottom face

of the bar, each of said pieces having another face which is perpendicular to said opposite parallel faces thereof and which constituted a portion of one of the vertical sides of said bar and includes one of said vertical side grooves in the center thereof, and another face of each piece being opposite to said perpendicular face thereof and which constituted a portion of one of said sloping channel sides; and combining the complementary pieces in pairs so as to form tapered two-piece magnets with the vertical grooves of each pair of pieces placed together so as to form a central hole through each tapered two-piece magnet.

15. 12. The method of making magnets each having a central hole therethrough which comprises, casting difficultly machinable permanent magnet metal in the form of a rectangular bar having a pair of vertically opposite deep channels extending longitudinally in the top and bottom faces thereof of such depth as to leave only a relatively thin section therebetween, and having a plurality of regularly spaced vertical grooves in one side thereof, chopping said bar at right angles to its length into relatively short lengths each of which includes one of said vertical side grooves, breaking each of said short lengths in two at the thin section thereof so as to form two different groups of uniformly shaped pieces one of the groups of pieces having one of said vertical grooves in one side of each piece, and combining each piece of one group with one of the pieces of the other group so as to form two-piece magnets with the vertical groove in one piece of each magnet providing a central hole therethrough.

MITCHELL P. CHRISTENSEN.
